UNITED STATES PATENT OFFICE.

WILLIAM SHAKESPEARE, JR., OF KALAMAZOO, MICHIGAN, ASSIGNOR, BY MESNE ASSIGNMENTS, TO SHAKESPEARE PRODUCTS COMPANY, OF KALAMAZOO, MICHIGAN.

BROOM.

Application filed March 27, 1922. Serial No. 547,039.

To all whom it may concern:

Be it known that I, WILLIAM SHAKESPEARE, Jr., a citizen of the United States, residing at the city and county of Kalamazoo, State of Michigan, have invented certain new and useful Improvements in Brooms, of which the following is a specification.

This invention relates to improvements in 10 brooms.

The main objects of my invention are:

First, to provide an improved broom in which the handle is detachably secured to the body so that the body may be renewed 15 by the user.

Second, to provide a structure having these advantages in which the parts are very economical to produce, light in weight and easily assembled and at the same time when 20 assembled the handle is very securely attached to the broom body.

Further objects, and objects relating to structural details, will definitely appear from the detailed description to follow.

25 I accomplish the objects of my invention by the devices and means described in the following specification. The invention is clearly defined and pointed out in the claims.

A structure which is a preferred embodiment of my invention is clearly illustrated 30 in the accompanying drawing, forming a part of this application, in which:

Fig. I is a side view of a broom embodying the features of my invention, the handle and brush body being partially broken away.

Fig. II is a detail vertical section on a line corresponding to line 2—2 of Figs. I and III, the handle being shown in full lines.

Fig. III is a horizontal section on a line 40 corresponding to line 3—3 of Figs. I and II.

Fig. IV is a horizontal section on a line corresponding to line 4—4 of Figs. I and II.

Fig. V is a plan view of the blank from 45 which one of the clamping member lugs is formed.

In the drawing similar reference characters refer to similar parts throughout the several views, and the sectional views are taken looking in the direction of the little 50 arrows at the ends of the section lines.

Referring to the drawing, 1 represents the broom body which is made as a complete assembled unit, that is, it is formed as a unit independent of the handle instead of 55 being assembled thereon in course in manu-

facture as is quite general practice in the manufacture of brooms.

The broom body is provided with a wire clamping band 2 disposed in a spaced relation to its upper end and has a central notch-like recess 3 in its upper end. The handle 4 is provided with a tapered portion having a thread 5 cut therein, there being a conical tip 6 below the thread—see Fig. II.

I provide a pair of clamping members 7 formed as sheet metal stampings and having beads 8 at their lower edges providing grooves engaging the band 2. The end edges of the clamping members are cut away at 9 above the band. Each head member has a 70 central convexed portion 10 struck therefrom, such portions having horizontal slots 11 therein.

The lugs 12 are also sheet metal stampings and are provided with tongues 13 and 14 which are disposed through the horizontal slots and folded upon the outer sides of the convexed portions of the clamping members. The head members also have semi-circular handle engaging portions 15 at their 80 upper ends. The lugs 12 have holes 16 therein. The outer edges of these lugs have curved flanges 17 which engage the threads of the handle thereby preventing their cutting into the end tip and avoiding the necessity of a metal tip for the handle.

The convexing of the clamping members stiffens the same at the point where the clamping stress of the lugs is applied, so that the clamping members may be formed 90 of comparatively light metal, which is a feature to be desired. The clamping members are arranged in opposed relation upon the brush body with their beads engaging the clamping band and their lugs overlapping within the recess 3 of the body. The handle is then threaded into the lugs and into the broom body below the lugs. The tapered conical tip 6 of the handle assists in threading it into the compressed broom 95 body and also guides the handle straight into the body. The clamping members are not connected in any way except through the handle as described, there being no pivotal connection, so that considerable variations in handles are possible without materially affecting the clamping action.

The parts of my improved broom are simple and economical to produce, the clamping members being duplicates and may, as 110

stated, be made of comparatively light material and at the same time have sufficient strength and rigidity for the purpose. The handle is very securely and rigidly attached and at the same time it is practical for the user to remove the same when it is desired to substitute another body.

Having thus described my invention, what I claim as new and desire to secure by Letters Patent, is:

1. In a broom, the combination with a broom body assembled as a unit and provided with a wire band spaced from its upper end, said body being centrally recessed above said band, of a wood handle provided with a tapered lower end having a screw thread cut therein, there being a conical tip below the thread, a pair of independent sheet metal clamping members having beads at their side lower edges providing inwardly facing grooves engaging said band, the end edges of said clamping members being cut away above the band, said clamping members having horizontally slotted convexed portions struck centrally therefrom and opposed semi-circular handle engaging portions on their upper edges, and a pair of inwardly projecting sheet metal lugs having tongues disposed through said slots in said clamping members and clamped upon said convexed portions thereof and holes to receive the handle, said clamping members being arranged with their lugs in opposed overlapping relation within said recess of said body and said handle screwed into the lugs and into the body below the same whereby the clamping members are clamped upon the body and the handle secured thereto.
2. In a broom, the combination with a broom body assembled as a unit, of a wood handle provided with a tapered lower end having a screw thread cut therein, there being a conical tip below the thread, a pair of independent sheet metal clamping members having horizontally slotted convexed portions struck centrally therefrom and opposed semi-circular handle engaging portions on their upper edges, and a pair of inwardly projecting sheet metal lugs having tongues disposed through said slots in said clamping members and clamped upon said convexed portions thereof and holes to receive

the handle, said clamping members being arranged with their lugs in opposed overlapping relation and said handle screwed into the lugs and into the body below the same whereby the clamping members are clamped upon the body and the handle secured thereto.

3. In a broom, the combination with a broom body assembled as a unit and provided with a binding band spaced from its upper end, of a wood handle provided with a tapered lower end having a screw thread cut therein, there being a conical tip of substantial length below the thread, a pair of clamping members having beads at their side lower edges providing inwardly facing grooves engaging said band, the end edges of said clamping members being cut away above the band, said clamping members having opposed handle engaging portions on their upper edges, and inwardly projecting sheet metal lugs having holes therein to receive said handle, said clamping members being arranged with their lugs in opposed overlapping relation and said handle screwed into the lugs and into the body below the same whereby the clamping members are clamped upon the body and the handle screwed thereto.

4. In a broom, the combination with a broom body assembled as a unit and provided with a binding band spaced from its upper end, of a handle provided with a tapered threaded lower end, a pair of clamping members disposed with their lower edges engaging said band, said clamping members having horizontally slotted convexed portions struck centrally therefrom and opposed handle engaging portions on their upper edges, and inwardly projecting lugs having tongues disposed through said slots in said clamping members and clamped upon said convexed portions thereof and having holes therein to receive said handle, said clamping members being arranged with their lugs in opposed overlapping relation and said handle screwed into the lugs and into the body below the same whereby the members are clamped upon the body and the handle secured thereto.

In witness whereof, I have hereunto set my hand and seal.

WILLIAM SHAKESPEARE, Jr. [L.S.]
